United States Patent Office.

WILLIAM DRIPPS, OF COATESVILLE, PENNSYLVANIA.

Letters Patent No. 96,405, dated November 2, 1869.

IMPROVED PROCESS OF RESTORING AND PRESERVING DECAYING RAILROAD-TIES.

The Schedule referred to in these Letters Patent and making part of the same.

To all whom it may concern:

Be it known that I, WILLIAM DRIPPS, of Coatesville, in the county of Chester, and State of Pennsylvania, have invented a new and improved Process of Restoring Decayed Railroad-Ties to their Original Durability; and I do hereby declare that the following is a full, clear, and exact description of the same.

It is the practice on railroads, when making a general repair, to take up all the ties, though seven-eighths of them may be good, provided they could be prevented from becoming any more decayed and unserviceable.

To prevent decay, and restore to such worthless ties an intrinsic value, and to prevent the loss of ties only partially deteriorated, is the object of my invention; which consists in infusing, as far as possible, throughout the chinks and cracks, cells, and rotted portions of such partially-decayed ties, and in coating their surfaces with a heated liquid preparation of gas-tar and sharp sand, which arrests further decay, and renders the ties fit to be put down again.

Such liquid preparation is composed of one part gas-tar, and three parts sharp sand.

I contemplate no exclusive process for accomplishing the end in view, but have in mind, as one method, to place a number of the removed ties, after being thoroughly dried in an oven, or any other way, within a close vessel, with a sufficient quantity of the composition, which vessel is provided with means of rotation, and a steam-tight case surrounding it. Steam is ad-

mitted through an opening in the centre of the journal, (or pivot,) and passes through an opening in the end of the vessel, and enters between the inside and outside casing, where it should remain long enough to boil the composition, the cylinder or vessel being, preferably, kept in motion, so that the composition will be thoroughly mixed and distributed through and over the ties, when I shut off the steam, and allow the vessel and contents to cool before removal.

The process may, however, be carried on in an open boiler, when means of stirring are supplied.

It is only when ties are partially decayed, or cracked, or otherwise unsound, that this process applies effectively, as, when the ties are new, there are no channels for the entry and lodgement of the composition.

I do not wish to limit myself to the use of the composition herein described, but wish to be at liberty to use any liquid or plastic composition which my process will admit of, and which will answer the same purpose.

Having thus described my invention,

What I claim as new, and desire to secure by Letters Patent, is—

The process, herein described, of restoring and preserving partially-decayed railroad-ties or sills to a valuable condition, substantially as described.

WILLIAM DRIPPS.
